[57] **CLAIM**

The ornamental design for a reduced profile cam helix for a torque responsive actuation device, as shown and described.

DESCRIPTION

FIG. 1 is a elevation perspective view of a profile cam helix for a torque responsive actuation device showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.
